CYCLIC CIRCUIT CONTROLLER

Kaj S. Christensen, Norwalk, Conn., assignor to
 Automatic Signal Corporation, East Norwalk,
 Conn., a corporation of Delaware

Application December 18, 1940, Serial No. 370,587

24 Claims. (Cl. 200—27)

The present invention relates generally to cyclic electric circuit controllers and more particularly to an improved controller of this type adapted to switching circuits in a predetermined sequence of time periods.

Controllers of this type are particularly well adapted for controlling signal circuits in street traffic signalling systems operating the usual "Go" and "Stop" signals through a time cycle, and the controller of the present invention is described in this specification as applied to such a signalling system although it will be understood that it is not limited to such application.

A cyclic controller in accordance with the present embodiment of the invention includes a timed rotating dial having keys adjustably spaced on its face and a rotary step-by-step sequence switch actuated in step by the several keys in sequence through an intermediate ratcheting mechanism which I believe to be novel in this connection. In traffic signal systems the sequence switch controls the signal circuits as actuated by the keys of the rotary timing dial, through the ratchet mechanism. The various combinations of signal circuits energized in the several steps or switch positions are determined by the sequence switch, and the time periods during which the sequence switch remains in the respective positions are determined by the spacing of the keys in the rotating dial, with the total cycle time determined by the speed at which the dial rotates.

It is a general object of the invention to provide an improved rotating dial type of circuit controller of simple and sturdy construction and smooth reliable operation.

Another object of the invention is to provide a circuit controller in which a step-by-step circuit switching mechanism is actuated by adjustably spaced keys in a rotating dial through a ratchet mechanism in which a continuous reciprocating drive is made effective to rotate the stepping switch one step by each key as the key passes a predetermined point in the rotation of the dial.

A further object of the invention is to provide a circuit controller in which a step-by-step switch is stepped from one step to another through actuation by keys in a rotating dial, and in which actuation by the keys moves a reciprocating pawl into operating relation with a ratchet wheel connected with the step-by-step rotary switch, the reciprocating pawl being placed in operating position by means of a cam guide member which is actuated by the passage of the key as the dial rotates.

Another object of the invention is to provide a circuit controller of the type described in the preceding paragraph and in which the dial has a large number of uniformly spaced positions for insertion of the several keys selectively and the movement of the reciprocating pawl is coordinated with the rotation of the dial so that the pawl has one complete reciprocating movement while the dial rotates through the angle between 5 successive positions.

An additional object of the invention is to provide a circuit controller of the type disclosed and in which the reciprocating drive is made effective to operate the ratchet mechanism to rotate 10 the step-by-step switch by a manually controlled means.

Another object of the invention is to provide a circuit controller of the type disclosed and in which the reciprocating drive is made effective 15 by an actuating means at a particular point in the cycle of the rotating dial to operate the ratchet mechanism to provide one cycle of rotation of the step-by-step switch by the dial responsive to a single actuation of the actuating means.

Other objects and features of the invention will be apparent from the following description and claims.

The nature of the preferred embodiment of the invention will be more fully understood by reference to the following description and accompanying drawings.

Fig. 1 shows an exploded view of the circuit controller with part of the dial in the foreground cut away to show the means by which the keys in the dial actuate circuit controller.

Fig. 2 shows the driving mechanism for the rotating dial, including a selective gear train.

Figs. 3 and 4 show respectively two operating positions of the reciprocating pawl and associated cam and guide members of Fig. 1. Fig. 3 shows the position of these parts when the reciprocating pawl is ineffective to operate the ratchet wheel and Fig. 4 shows these parts when they are actuated, by a key in the dial for example, to render the pawl effective to operate the ratchet.

Fig. 5 shows a schematic diagram of alternative controls for the operation of the circuit controller.

Fig. 6 shows in more detail the electromagnet XR of Fig. 5 and its controlling connection with guide member 154 of Fig. 1, to make the reciprocating drive effective to start the switch cam-

shaft through a cycle responsive to traffic actuation.

Considering now the principal operating parts of the controller and their mode of operation as illustrated in the present embodiment, reference may be had to Figs. 1 and 2. In Fig. 1 the rotating dial 121 is shown largely cut away at the far left side of the figure, and this rotating dial 121 appears more fully, although still partially cut away for illustrative purposes, at the top of Fig. 2.

The disc 121 is rotated at uniform speed by a motor M through a train of gears illustrated in Fig. 2. Dial 121 is provided with two concentric rows of holes 130 and 131. A number of keys, corresponding to the number of positions of the cyclic switch of the controller, are placed in selected holes 130 at desired spacing, including one long key and several short keys.

The cyclic switch has a number of cams and contacts operated thereby, of which one cam 183 and one pair of contacts C4 are illustrated in Fig. 1 and additional such cam contacts are shown schematically in Fig. 5. The contacts may be connected to signalling circuits, for example. These cams are of varying shapes in accordance with the portions of the signal switching cycle in which it is desired to have the several circuits closed. These cams are rigidly mounted on cam-shaft 140, and a pair of ratchet wheels 145 and 152 are also attached to this camshaft.

A double pawl and crank arm assembly, illustrated in the foreground of Fig. 1, is constantly reciprocated by an eccentric drive disc 137 which is rotated by a part of the gear train of Fig. 2. The position of the two pawls 146 and 156 of this assembly with respect to the ratchet wheels is controlled by the guides 149 and 154, and guide control cams 148 and 153, which are controlled in turn by the keys in the row of holes 130 in the dial. As keys in the dial rotate past the cams 148 and 153, the long key actuates the cam 153 once per cycle and the short keys actuate the cam 148 successively during the remainder of the cycle, actuation by these keys raising the guides 149 and 154 and shifting the position of the pawls 146 and 156 so that they will engage the respective ratchet wheels 145 and 152 during one stroke of the reciprocating pawl and crank arm assembly, and thus rotate the signal switch camshaft one step for each key actuation. The signal switch camshaft is thus stepped through one revolution for each revolution of the rotating dial, with the timing of the several steps determined by the spacing of the keys in the dial.

Considering the circuit controller now in more detail, the dial 121 rotates on a bearing surface on member 129, shown in Fig. 2, which may serve also as a thrust bearing for the dial and may be threaded internally or externally so as to screw into or on the shaft 140 on which the ratchet and cams are mounted, or into a supporting plate or panel (not shown). In either case the dial 121 rotates freely on an outer bearing surface on member 129 and independently of the movement of the shaft 140.

As previously described the dial 121 is rotated through a train of gears by the motor M shown in Fig. 2. This is preferably a self-starting synchronous motor for operation in synchronism with an alternating current power supply, but other types of timing motors may be used if such synchronism is not desired. The shaft 135 shown at the left of the dial 121 in Fig. 2, is rotated by a part of the same train of gears so that it also turns at a uniform speed, preferably a speed

100 times as fast as the dial 121 where the dial has 100 holes 130.

A disc 137 rotates with shaft 135 and has an eccentric pivot 138 on its face. Link 139 connects pivot 138 with the lower end of L shaped bell crank 142 at pivot 141, so that the rotation of the shaft 135 causes the bell crank 142 to reciprocate, the lower arm of the bell crank reciprocating to the right and left and the upper arm reciprocating up and down.

At the upper end of the bell crank 142 a shaft 144 is rigidly secured, and a pawl 146 is pivoted on this shaft. Pawl 146 is preferably urged in a counterclockwise direction on shaft 144 by spring member 151, so that its lower end is free of the ratchet wheel 145 and its upper end bears against the guide member 149.

Guide 149 is pivoted at 218, on a supporting frame or panel (not shown), and is normally urged in a counterclockwise direction by a spring 150 against the cam member 148 which is pivoted on shaft 147. The guide 149 bears against the lower end of the cam 148.

Keys or pins 132 are placed at desired spacing 25 in selected holes 130 in the inner ring of holes on the dial 121 and project out of the back of the dial some distance. These pins, as they pass the uppermost position as the dial rotates, bear against the upper end of the pivoted cam 148. 30 The dial 121 rotates clockwise and the key 132, for example, will depress the upper right hand end of the pivoted cam 148, thereby raising the lower left hand end. This causes spring 150 to raise the guide 149, rotating it very slightly in a counterclockwise direction on its pivot 219 so that its outer end raises the upper end of the pawl 146. This presses the lower end of the pawl 146 into engagement with the ratchet wheel 145 so that as the eccentric drive causes the bell 35 crank 142 to reciprocate, the pawl 146 will move the ratchet wheel 145 clockwise one tooth. The gear ratio between the eccentric drive member 137 and the disc 121 is set so that each key 132 will actuate the cam 148 only long enough to have pawl 146 make one stroke.

The turning of the ratchet wheel 145 one tooth by the actuation of the key 132 rotates the shaft 140 clockwise through one step. This camshaft 140 has rigidly attached thereto in desired angular relationship one or more cams, of which one is illustrated as cam 123. Cam 123 has a projecting lobe which raises the lower contact member of the pair of contacts C4 to close these contacts when the projecting lobe is rotated around to the top position. The contacts C4 may control a work circuit to open and close the circuit alternately for whatever proportions of the signal cycle desired, and the cam 123 is shaped to have the projecting lobe extend through the desired 55 part of the total cycle corresponding to the number of teeth of the ratchet wheel 145 in such part of the cycle.

Ordinarily when this controller is used as a traffic signal circuit controller four or more signal circuit cams and contacts will be employed 60 on shaft 140, six cams and contacts ordinarily being used for a signal cycle providing green, yellow, and red signal periods for each of two intersecting streets, for example. With a four period signal cycle the camshaft 140 can have four or more steps, or any desired multiple of 4, and with a six period signal cycle the camshaft 140 can have six or more steps, or any multiple of 6, with a corresponding number of positions 65 of the ratchet wheel 145, and a corresponding

number of keys in the inner row of holes 131 in the rotating dial 121. Where more steps are used than the number of signal periods the additional steps are preferably inserted in one or more of the longer signal periods, with the signals remaining unchanged in these extra steps.

In order to assure that the camshaft 140 will be resynchronized with the rotating dial 121 at least once in each cycle, if they should for any reason have become out of step during the cycle, one key 133 is made longer than the keys 132 and projects farther back of the dial 121. This key is shown in Fig. 1 near the top of the dial 121, and is shown with a break in it merely to indicate that it is considerably shorter than appears in the exploded form of Fig. 1, in which the several parts along the shaft 140 near the left end of the shaft are shown much further spread apart than in actual construction, in order that the view of those parts in front will not block that of others behind.

Crank arm 143 is rigidly attached to the outer end of the upper arm of bell crank 142 by means of the short shaft 144, which is shown broken in Fig. 1 merely to indicate that it appears much longer in the exploded view than in actual construction. The crank arm 143 reciprocates with the upper arm of the bell crank 142, and pawl 156 is pivoted on shaft 144 at the outer end of the crank arm 143. This pawl 156 bears against guide 154 which is pivoted at the bearing member 211 and which is urged in a counterclockwise direction around this bearing by the spring 155 against the cam 153 which is pivoted on shaft 147, but turns freely on this shaft just as does the similar cam 148.

The ratchet wheel 152 is provided with one tooth in position to be actuated by pawl 156 at one point in the cycle of the camshaft 140, whenever the guide 154 is raised by action of the cam 153. Cam 153 is rotated slightly clockwise when the long key 133 passes the uppermost position during rotation of the dial. One such long key 133 is used for each cycle of the camshaft 140. The ratchet wheel 145 has one blank position where a tooth is omitted corresponding to the position of the single tooth on ratchet wheel 152. As the dial 121 rotates the several keys 132 actuate the ratchet wheel 145 through its several steps until the blank tooth position is reached. At this point in the camshaft cycle only the long key 133 is able to advance the camshaft by actuation of the cam 153 to raise the guide 154 and move the pawl 156 into position to engage the single tooth of the ratchet wheel 152 during one stroke of the bell crank 142 and associated crank 143.

When the camshaft 140 has 12 positions in its cycle as illustrated by the teeth on the ratchet wheels 145 and 152 in Fig. 1, eleven short keys 132 and one long key 133 are placed in desired positions in the inner row of holes 130 in the face of the dial 121. It will be understood, therefore, that the uniform rotation of dial 121 at a predetermined speed determines the total cycle length of the circuit controller and any signal cycle controlled thereby, and the relative spacing of the keys in the inner row of holes 130 in the dial determines the division of the cycle into various parts of desired length for the several positions.

The combinations of signal circuits energized in the different positions are determined by the shape of the signal cams on the shaft 140 and on the connections from the cam controlled contacts to the signal circuits.

In the present controller a local pair of contact members 171, 172 are placed as shown in Fig. 1 near the top of the dial 121 in position to be actuated by key 134, which is placed at the desired position in the outer row of holes 131 in the dial. When key 134 is rotated past the uppermost position it raises the contact member 171 to separate it from contact member 172.

For the purpose of better illustration of the action of the cam member 153 and the guide member 149 and the pawl 146, these several members are shown in two different operating positions in Figs. 3 and 4. Fig. 3 shows the several parts in the normal resting position between actuations by the keys in the inner ring of holes 130 of the dial 121. In this normal resting position the guide 149 is held in a depressed position by the left end of the cam 148, and the left or upper end of the pawl 146 is thus in its lower position so that the lower end of the pawl 146 extends to the right and out of range of the teeth of the ratchet wheel 145.

In Fig. 4 the cam 148 is shown turned slightly clockwise so that the guide 149 is raised to its upper position to raise the upper end of the pawl 146 and thus deflect the lower end of this pawl to the left to place it in position to engage the ratchet wheel 145. The guide 149 is constantly urged against the cam 148 by the spring 150 which is shown in Fig. 1 but is omitted for simplicity of illustration in Figs. 3 and 4. Similarly the pawl 146 is urged against the guide 149 by spring means or by gravity or if desired it may be arranged to be maintained in either of its alternate positions by friction and to be moved out of reach of the teeth of the ratchet 145 on return strokes of the bell crank member.

The gear train between the driving motor M and the rotating dial 121 and eccentric disc 137 preferably includes means for selecting gears to provide a speed changing arrangement for the dial 121, in order to provide longer or shorter total cycles as desired. A preferred gear changing arrangement is illustrated in Fig. 2, in which the motor drives gear 112 in a counterclockwise direction on the motor shaft 111. Gear 114 is driven in mesh with gear 112, gear 114 rotating in a clockwise direction and having attached thereto the gear 115. The gears 114 and 115 rotate on the short shaft 113 which is rigidly fixed in the sector 118 which is pivoted on the shaft 117 at the center of the gear 119, and has its lower periphery serrated to engage gear 124 which is pivoted on shaft 126. Gear 124 engages gear 125 which is rigidly attached to the shaft 123. At the outer end of the shaft 123 is placed the adjustment knob 122.

The gear 125 and the gear 124 and sector 118 are normally held in position with the gear 114 in mesh with gear 112, by means of the locking pin 127 which engages the teeth of the gear 125. The adjusting knob 122 may be pulled out a short distance to pull out the shaft 123 and the gear 125 to free the latter from the pin 127, while still engaging gear 124, and by turning the knob 122 the gears 125 and 124 will be rotated to turn the sector 118 to free the gear 114 from the driving gear 112 so that a different gear may be substituted for gear 114 to provide a different gear ratio between the driving gear 112 and the driven gear combination 114-115. When the substitute gear is in place the adjustment knob 122 is turned clockwise until the new gear 114 meshes with gear 112, and the adjusting knob and shaft 123 and gear 125 will then be returned to their back

position to be held in place by the short locking pin 127, by means of a return spring not shown.

The driven gear 115 on shaft 113 on the sector 118 meshes with gear 119 to which is rigidly attached the gear 120 which in turn meshes with the serrations on the periphery of the dial 121 to rotate the latter. Arrows are shown on the several gears Fig. 2 to show their direction of rotation. Gear 119 also meshes with gear 136 on shaft 135 to rotate the eccentric disc 137 as shown in Fig. 2.

Provision is made in the circuit controller to interrupt the normal dial key actuation of the camshaft 140 and to substitute manual actuation if desired, so that the camshaft will remain at rest in any desired signal circuit position until manual actuation causes it to step to the next position.

At the forward end of the shaft 147 in Fig. 1, appearing in front of the cam 148, is a small plate 157, which is rigidly attached at its lower end to the shaft 147. At the upper end of this plate 157 is rigidly attached a shaft 158 extending over the cams 148 and 153. At the rear end of the shaft 147 is rigidly attached a crank arm 160. At the outer end of the crank arm 160 a link member 161 is connected at pivot 162. The right hand end of the link member 161 is connected to an armature plate 163 which is pivoted at its lower end 164. The link member 161 is pivoted at the top of the plate 163 on the pivot 165.

During the ordinary automatic drive of the camshaft 140 by means of the pins in the dial, the armature plate 163 is in the position shown in Fig. 1 with the crank arm 160 in a vertical position and with the plate 157 and its shaft 158 slightly free of the cams 148 and 153. When the armature plate 163 is rotated slightly clockwise to the right on the pivot 164, the crank arm 160 is also rotated slightly clockwise to the right by the connecting link 161 and the shaft 147 is thus rotated slightly to the right, as are also the plate 157 at the forward end of the shaft 147, and the shaft 158. The shaft 158 in being turned toward the right about the shaft 147 as an axis, rotates the cams 148 and 153 clockwise to the right sufficiently so as to move the upper end of the cam 148 out of range of actuation by the pins 132 and 133 and similarly cam 153 is moved out of range of actuation of pin 133, and these cams 148 and 153 are turned so as to bear against the right hand projection on the top of the guides 149 and 154.

By rotating the shaft 147 and the plate 157 and its associated shaft 158 to the position shown in Fig. 4 the guides will place the pawls 146 and 156 in position to engage the ratchet wheels 145 and 152 respectively at each stroke of the reciprocating action of the bell crank 142 as driven by the eccentric disc 137. By turning the shaft 147 further in a clockwise direction by turning the armature plate 163 further to the right the cams 148 and 153 will be turned so that the projection near the right end on the lower side of these cams will depress the guides 149 and 154 so as to release the pawls 146 and 156 from the ratchet wheel. Thus by controlling the position of the armature plate 163 the eccentric reciprocating drive can be made effective or ineffective to rotate the camshaft as desired.

At the upper end of Fig. 1 a preferred arrangement is illustrated for controlling the position of the armature plate 163 to serve as a manual con-

trol of the notching of the camshaft. An adjusting knob 170 is rigidly attached to shaft 167 at the forward end, and a cam 168 is rigidly attached at the rear end of this shaft 167. The shaft 167 passes through a supporting plate 159 on the frame of the circuit controller which may also serve as a bearing for the shaft 147 as well as the shaft 167.

The adjusting knob 170 has two positions indicated on the frame member 159 as automatic and manual positions. In the automatic position to the left as shown in Fig. 1 the cam 168 is in a vertical position, free of the armature plate 163. If the adjusting knob 170 is turned to the right, however, to the manual position, the cam 168 is also turned to the right to move the armature plate 163 from its stop 166 so as to rotate the cams 148 and 153 to the positions shown in Fig. 4 in which the pawls are continuously effective to rotate the ratchet wheels and camshaft.

There is also rigidly mounted on shaft 167 an additional cam 169 which is rotated with the shaft 167 to close the pair of contacts SM in the manual position of the adjusting knob 170. The closing of contacts SM prepares a circuit to energize the magnet MR at the upper end of Fig. 1 to pull the armature plate 163 still further to the right away from the cam 168 and correspondingly to rotate the shaft 147 and the cams 148 and 153 further to the right to depress the guides 149 and 154 sufficiently to free the pawls 146 and 156 from the ratchet wheels so that no ratcheting of the camshaft will occur although the normal synchronous drive and rotation of disc 121 will continue.

By placing a manually controlled switch in the circuit of the magnet MR this magnet can be energized or deenergized as desired. In the present preferred arrangement the circuit through the switch is normally closed in absence of manual actuation and the magnet MR is normally energized holding the armature plate 163 in its furthest position to the right so that the automatic ratcheting action is interrupted and the signal camshaft 140 remains at rest. The manual switch is arranged to be opened by manual actuation, to deenergize the magnet MR and allow the armature plate 163 to move slightly to the left until it contacts the projection on cam 168, which has been turned to the right in the manual position now being described. This slight movement of the armature plate 163 to the left allows the cams 148 and 153 to move slightly counter clockwise to allow the guides 149 and 154 to assume the position shown in Fig. 4 in which the reciprocating action of the pawls 146 and 156 is effective to ratchet the camshafts.

The circuit for magnet MR for manual control is shown in preferred form in Fig. 5, extending from the right hand power wire 185 via wire 181, magnet MR, switch SM, wire 183 to junction point 212. At this point the circuit is divided into two branches, the first branch via cam contact C1a and wire 200 to upper contact 213 of switch ST, and the second branch via cam contact C1b and wire 199 to lower contact 214 of switch ST. The circuit then continues via switch ST and wire 201 to the left hand power supply wire 184.

The power supply wires 185 and 184 are marked positive and negative respectively at the top of Fig. 5 for convenience but it will be appreciated that in the preferred form of the invention with an alternating current synchronous driving mo-

tor M the power supply will be alternating current.

The switch SM is closed when the selector knob 170 is turned to the manual position as previously described, and this places magnet MR under control of manual switch ST and cam contacts C1a and C1b. The switch ST may preferably be of the well known rotary toggle type for example so that each time it is pushed it will reverse its position and then will remain in the last reversed position until again pushed, when it will reverse to the original position. Thus switch ST will be alternated between its contacts 213 and 214 by successive manual actuations.

As shown in Fig. 1 the cam contacts C1a and C1b are lower and upper contacts controlled by cams 181 and 182 on the signal switch camshaft and closed alternately by action of cam 182.

Traffic actuated control of the signal cycle can be provided in the present controller if it is desired, and the mechanical features of the apparatus for making the reciprocating drive effective to advance the signal camshaft responsive to traffic actuation are shown in Fig. 6.

A traffic actuated relay DR controls the starting of the controller through a signal cycle by means of the electromagnet XR and a mechanical connection with the guide 154 as shown in Fig. 6, to control the engagement of the pawl 156 with the ratchet wheel 152 as the pawl 156 is regularly raised and lowered by the reciprocating drive.

When this traffic actuated feature is desired in the controller the traffic detector relay DR is provided and the magnet XR and the mechanical linkage of Fig. 6 are added and arranged to maintain the guide 154 depressed in the absence of traffic actuation.

Considering now in more detail the control of the guide member 154 by the magnet XR and in turn by the detector controlled relay DR, reference may best be had to Fig. 6. The guide members 149 and 154 and their respective pivots 210 and 211 are shown in the foreground of Fig. 6 for orientation with the showing of Fig. 1, but for convenience of illustration the semi-perspective view is shown from the left side in Fig. 6 as compared with the showing from the right side in Fig. 1.

A small cam 173 bears against the top of the guide member 154. This cam 173 is rigidly attached to the shaft 174 which passes through a bearing in the frame member 159. A crank arm 175 is rigidly attached to the rear end of the shaft 174, and a link 176 connects the crank arm 175 at the pivot 177 with the armature 178 of the electromagnet XR. The link 176 bears on the pin 180 as a pivot, and the armature 178 operates on the pivot 179 at the top.

The several parts are shown in Fig. 6 in position corresponding to traffic actuation, with the magnet XR deenergized and the lower part of armature 178 swung to the right so that the shaft 174 and the cam 173 allow the guide member 154 to come up to its normal resting position against the lower left hand end of the cam 153 shown in Fig. 1. In this position the pawl 156 is still held out of engagement with the ratchet wheel 152 but as soon as the rotary dial rotates the key 133 to the top position the cam 153 will be turned slightly and the guide 154 will be raised to make the pawl 156 effective to engage the ratchet wheel 152 and advance the camshaft from position 12. Such action by the key 133 would be impossible,

however, if the cam 173 were in its lower position as it would be in absence of actuation so that in absence of actuation the long key 133 would be ineffective to raise the guide 154 to permit the advancement of the camshaft from position 12.

Normally in the absence of traffic actuation the magnet XR is energized over a back contact dr2 of the relay DR when the latter relay is in its deenergized position. This circuit may be traced from the negative power wire 184 via wire 209 contact dr2, electromagnet XR, wire 196 to positive power wire 185. Thus the normal energization of magnet XR in absence of traffic actuation will hold the lower end of the armature 178 to the left and maintain shaft 174 and the cam 173 turned clockwise a small amount to maintain the guide 154 in a depressed position. When traffic actuation occurs and energizes relay DR as previously described the back contact dr2 will be opened so as to deenergize the magnet XR, allowing its armature 178 to fall back, for example by action of a spring not shown, to the position shown in Fig. 6, to allow the guide 154 to rise to the position where the long pin 133 can be effective to cause advancement of the camshaft from position 12.

It will be appreciated that with the arrangement described for traffic actuated control the signal camshaft will normally remain at rest in the absence of traffic actuation, and that after traffic actuation has occurred the cam shaft will still remain at rest in the same position until the long pin 133 reaches the top position in the current cycle of rotation of the dial. Thus where this arrangement for traffic actuation is employed at two or more controllers of this type, driven by synchronous motors from a common alternating current power supply, or maintained in synchronism by a master controller, the signal camshafts of the two controllers will each be individually responsive to traffic actuation in predetermined time relation with their own dials, and with the master controller if one is used, and when both are actuated they will operate through their cycle in predetermined time phase relation with each other, as determined by the positions of the long pin 133 in the dial of each controller.

It will be understood that further changes in the character and arrangement of the various parts or substitution of equivalent parts or arrangements of apparatus may be made without departing from the spirit of the invention as defined by the claims.

I claim:

1. A cyclic circuit controller including a step-by-step cyclic switch, ratchet means operable to advance said cyclic switch from one step to another in its cycle, a continuously operating reciprocating means, and means for selectively connecting and disconnecting said reciprocating means to and from said ratchet means to operate said ratchet means to so advance said cyclic switch when connected.

2. A cyclic circuit controller including a step-by-step cyclic switch, ratchet means, time controlled means for reciprocating said ratchet means at a determined time rate, and means synchronized with said time controlled means for selectively connecting and disconnecting said ratchet means to and from said cyclic switch to advance said cyclic switch at desired time intervals.

3. A cyclic circuit controller including a step-by-step cyclic switch, ratchet means, time controlled means for reciprocating said ratchet means at a determined time rate, and means for selectively connecting and disconnecting said ratchet means to and from said cyclic switch to advance said cyclic switch from one step to the next by each reciprocation when connected, a shaft rotating in synchronous time relation with said time controlled means, and means arranged in various desired angular positions on said shaft for actuating said selective connection means to connect said ratchet means to advance said shaft one step at a time at desired time intervals.

4. A cyclic circuit controller including a step-by-step cyclic switch, ratchet means, time controlled means for reciprocating said ratchet means at a determined time rate, and means normally disconnecting said ratchet means from said cyclic switch when non-actuated and connecting said ratchet means to said cyclic switch to advance the latter one step by each reciprocation of said ratchet means when actuated, a rotating disc having a plurality of projecting elements thereon in selected angular relation with its axis of rotation for actuating said ratchet connecting means for one reciprocation of the ratchet means for each such element.

5. A cyclic circuit controller including a sequence switch having a cycle of positions through which it is adapted to be operated step-by-step, a rotating dial having a plurality of keys thereon corresponding to the number of positions of said cycle, a constantly operating intermittent drive mechanism, and means engaged by said keys as said dial rotates to connect said intermittent drive mechanism momentarily to said sequence switch to drive the switch from one step to the next responsive to each key engagement.

6. A cyclic circuit controller including a sequence switch having a cycle of positions through which it is adapted to be operated step-by-step, a rotating dial having a plurality of keys thereon in selected angular spacing in relation to the axis of rotation of the dial, a constantly operating intermittent drive mechanism, and means engaged by said keys as said dial rotates to connect said intermittent drive mechanism momentarily to said sequence switch to drive the switch one step responsive to each key engagement for operating said switch through the several steps of its cycle at selected time intervals in accordance with the selected spacing of said keys.

7. A cyclic circuit controller including a sequence switch having a cycle of positions through which it is adapted to be operated step-by-step, a rotating dial having a plurality of keys thereon in selected angular spacing in relation to the axis of rotation of the dial, a constantly operating intermittent drive mechanism, and means engaged by said keys as said dial rotates to connect said intermittent drive mechanism momentarily to said sequence switch to drive the switch one step responsive to each key engagement for operating said switch through the several steps of its cycle at selected time intervals in accordance with the selected spacing of said keys, and means synchronizing the cycle of rotation of said dial with the cycle of said sequence switch.

8. A cyclic circuit controller including a sequence switch having a cycle of positions through which it is adapted to be operated step-by-step, a rotating dial having a plurality of keys thereon in selected angular spacing in relation to the axis of rotation of the dial, a constantly operating

intermittent drive mechanism, and means engaged by said keys as said dial rotates to connect said intermittent drive mechanism momentarily to said sequence switch to drive the switch one step responsive to each key engagement for operating said switch through the several steps of its cycle at selected time intervals in accordance with the selected spacing of said keys and means synchronizing each driving action of the intermittent driving mechanism with rotation of said dial through an angle which is the common divisor of all the angles between keys in said dial.

9. A cyclic circuit controller including a sequence switch having a cycle of positions through which it is adapted to be operated step-by-step, a rotating dial having a number of key positions evenly spaced therein and keys in selected positions, a constantly operating intermittent drive mechanism synchronized with said dial to conform the time spacing between successive driving actions of its intermittent drive to the time required for the dial to rotate between successive key positions and means engaged by said keys as said dial rotates to connect said intermittent drive mechanism momentarily to said sequence switch to drive the switch one step responsive to each key engagement for operating said switch through the several steps of its cycle at selected time intervals in accordance with the selected spacing of said keys.

10. A cyclic circuit controller including a sequence switch having a cycle of positions through which it is adapted to be operated step-by-step, a rotating dial having a plurality of keys thereon corresponding to the number of positions of said cycle, a ratchet wheel on said sequence switch, a reciprocating arm adjacent said ratchet wheel, a pawl pivoted on said arm so as to travel over a path adjacent said ratchet wheel as said arm reciprocates, a guide member bearing against said pawl during a part of the travel path and means actuated momentarily by each of said keys as said dial rotates to move said guide member to guide said pawl into engagement with said ratchet wheel to advance said sequence switch one step for each key.

11. A cyclic circuit controller including a rotary step-by-step sequence switch having a number of operating positions through which it is adapted to be operated cyclically, a ratchet wheel attached to said rotary switch, a time controlled motor, a pawl reciprocated continuously by said motor, a disc rotated continuously by said motor, a cam guide member cooperating with said pawl as the latter is reciprocated and having two operating positions, the first position to guide the pawl out of engagement with said ratchet wheel and the second position to guide the pawl into engagement, and a plurality of keys placed in selected angular positions on said disc to engage said cam guide member to shift said cam guide member from said first to said second position momentarily at selected time intervals as said disc rotates.

12. A cyclic circuit controller including a step-by-step sequence switch having a cycle of operating positions and corresponding switch operating combinations, a shaft rotating at constant speed, a ratchet wheel connected with said sequence switch, a pawl means operated by said rotating shaft to reciprocate said pawl over a path adjacent said ratchet wheel, means for guiding said pawl in said path for engagement with said ratchet wheel when actuated and for disengagement from said ratchet wheel when not

actuated, means operated cyclically by said rotating shaft to actuate said guiding means a plurality of times at selected time spacing in each cycle corresponding to the number of operating positions of said sequence switch.

13. A cyclic circuit controller including a step-by-step sequence switch having a cycle of operating positions and corresponding switch operating combinations, a shaft rotating at constant speed, a ratchet wheel connected with said sequence switch, a pawl means operated by said rotating shaft to reciprocate said pawl over a path adjacent said ratchet wheel, means for guiding said pawl in said path for engagement with said ratchet wheel when actuated and for disengagement from said ratchet wheel when not actuated, a disc rotated by said shaft, a plurality of keys in said disc in selected angular positions about the axis of rotation of the disc to actuate said guiding means momentarily as said disc rotates.

14. A cyclic circuit controller including a shaft rotatable through a cycle of a plurality of steps, switches operated by said shaft in the several steps, a ratchet wheel on said shaft, a second shaft rotating constantly, a pawl reciprocated by said second shaft over a path adjacent said ratchet wheel, a disc rotated by said second shaft, keys in said disc in selected angular positions with respect to the axis of rotation of the disc and projecting from said disc, a guide member bearing against said pawl, and a cam in position to be actuated momentarily by said keys as said disc rotates to control said guide member normally to maintain said pawl disengaged from said ratchet wheel throughout the reciprocating path when not actuated and to move said guide member to bring said pawl into engagement with said ratchet wheel in the reciprocating path to advance the first shaft when actuated.

15. A cyclic circuit controller including a shaft rotatable through a cycle of a plurality of steps, switches operated by said shaft in the several steps, a ratchet wheel on said shaft, a second shaft rotating constantly, a pawl reciprocated by said second shaft over a path adjacent said ratchet wheel, a disc rotated by said second shaft, keys in said disc in selected angular positions with respect to the axis of rotation of the disc and projecting from said disc, means guiding said pawl in said path and having two operating positions the first position to maintain said pawl disengaged from said ratchet wheel throughout said path and the second position to guide said pawl into engagement with said ratchet wheel to advance the wheel step-by-step as said pawl reciprocates in said path, and control means for selectively placing said guiding means in and out of the path of the keys in said rotating disc as desired to shift said guiding means from its first to its second position momentarily by passage of each key when said guiding means is in the path of said keys and to maintain said guiding means continuously as long as desired in its second position when placed out of the path of said keys.

16. A cyclic circuit controller including a shaft rotatable through a cycle of a plurality of steps, switches operated by said shaft in the several steps, a ratchet wheel on said shaft, a second shaft rotating constantly, a pawl reciprocated by said second shaft over a path adjacent said ratchet wheel, a disc rotated by said second shaft, keys in said disc in selected angular positions

with respect to the axis of rotation of the disc and projecting from said disc, means guiding said pawl in said path and having two operating positions, the first position to maintain said pawl

5 disengaged from said ratchet wheel through said path and the second position to guide said pawl into engagement with said ratchet wheel to advance the wheel step-by-step as said pawl reciprocates in said path, and control means selectively placing said guiding means in the path of movement of said keys in said rotating disc to shift said guiding means from the first to the second position momentarily by passage of each key or placing said guiding means out of such path

10 15 of said keys, said control means including means actuatable to shift said guiding means as desired from said first position to said second position and including a connection with the first mentioned shaft to maintain said guiding means in

20 25 said second position after such actuation and until said first shaft has been rotated to a predetermined one of its positions and then to release said guiding means to said first position until said actuatable means is again actuated.

17. A cyclic circuit controller including a shaft rotatable through a cycle of a plurality of steps, switches operated by said shaft in the several steps, a ratchet wheel on said shaft, a second shaft rotating constantly, a pawl reciprocated by

30 35 said second shaft over a path adjacent said ratchet wheel, a disc rotated by said second shaft, keys in said disc in selected angular positions with respect to the axis of rotation of the disc and projecting from said disc, means guiding said

35 pawl in said path and having two operating positions, the first position to maintain said pawl disengaged from said ratchet wheel throughout said path and the second position to guide said pawl into engagement with said ratchet wheel

40 45 to advance the wheel step-by-step as said pawl reciprocates in said path, and control means for selectively placing said guiding means continuously in its first position and out of the path of movement of said keys as said disc rotates or placing said guiding means in the path of said keys for shift of said guiding means from its first position to second position momentarily by passage of each of said keys

50 55 18. A traffic signal controller including a sequence switch having a cycle of positions through which it is adapted to be operated step-by-step to provide a cycle of a plurality of right of way signaling and intermediate change signalling conditions, a rotating dial having a plurality of keys at selected angular spacing thereon corresponding to the number of positions of said sequence switch, a constantly operating intermittent drive mechanism, and means engaged by said keys as said dial rotates to connect said intermittent

60 65 drive mechanism momentarily to said sequence switch to drive the switch one step responsive to each key engagement for operating said switch through the several steps of its cycle at selected time intervals in accordance with the selected spacing of said keys.

19. In a traffic signal controller having a step-by-step sequence switch with a plurality of switching positions through which it is adapted to be operated cyclically to provide a cycle of a plurality of right of way signaling conditions, a ratchet wheel connected with said sequence switch, a time controlled motor, a pawl reciprocated by said motor over a path adjacent said ratchet wheel, means guiding said pawl nor-

mally to maintain said pawl disengaged from said ratchet wheel and adapted to be actuated to guide said pawl into engagement with said ratchet wheel, a shaft rotating in predetermined time relation with said motor, actuating elements arranged in desired angular position on said shaft for actuation of said guide means, and electromagnetic means for engaging said guide means for rendering said guide means selectively ineffective and effective to be so actuated by one of said actuating elements to maintain said sequence switch normally in one of said positions when ineffective and to initiate a cycle of operation of said sequence switch by all of said actuating elements when effective.

20. In a traffic signal controller having a step-by-step sequence switch with a plurality of switching positions through which it is adapted to be operated cyclically to provide a cycle of right of way signaling conditions, ratchet wheel means connected with said sequence switch, a time controlled motor, pawl means reciprocated by said motor over a path adjacent said ratchet means, means guiding said pawl means normally to maintain said pawl means disengaged from said ratchet means and adapted to be actuated to guide said pawl means into engagement with said ratchet means, a shaft rotating in predetermined time relation with said motor, actuating elements arranged in desired angular position on said shaft, and control means for engaging said guide means to render the guide means selectively ineffective and effective to be so actuated by said actuating elements whereby said sequence switch will be maintained in one of said positions when said guide means is rendered ineffective and said sequence switch will be operated through the cycle of said positions when said guide means is rendered effective.

21. In a traffic signal controller as in claim 20, said control means including a cam having one position bearing against said guide means to render the latter ineffective to be so actuated and having a second position free of said guide means to render the guide means effective to be so actuated, and an electromagnetic device for operating said cam from one position to the other selectively.

22. In a traffic signal controller having a step-by-step sequence switch with a plurality of switching positions through which it is adapted to be operated cyclically to provide a cycle of right of way signaling conditions, a pair of complementary ratchet wheels connected with said sequence switch, one ratchet wheel having one ratchet tooth per cycle and the other ratchet wheel having the remainder of teeth to complete the cycle, a time controlled motor, a pair of pawls reciprocated by said motor over a path adjacent said ratchet wheels and cooperating with said ratchet wheels respectively, means guiding said pawls normally to maintain the pawls disengaged from the associated ratchet wheels and adapted to be actuated to guide said pawls into engagement with said associated ratchet wheels,

a shaft rotating in predetermined time relation with said motor, actuating elements arranged in desired angular position on said shaft and including one actuating element arranged for actuation of guide means only for engagement of said pawl associated with said one tooth ratchet wheel and the remainder of the actuating elements arranged for actuation of the guide means for said other pawl, and control means for rendering said guide means for the first mentioned pawl selectively ineffective and effective to be so actuated by said one of said actuating elements to maintain said sequence switch normally in one of said positions when ineffective and to initiate a cycle of operation of said sequence switch through said plurality of said positions by all of said actuating elements when effective.

23. In a controller having a step-by-step sequence switch with a plurality of switching positions through which it is adapted to be operated cyclically to provide a cycle of a plurality of signaling conditions, a ratchet wheel connected with said sequence switch, a time controlled motor, a pawl reciprocated by said motor over a path adjacent said ratchet wheel, means guiding said pawl normally to maintain said pawl disengaged from said ratchet wheel and adapted to be actuated to guide said pawl into engagement with said ratchet wheel, a shaft rotating in predetermined time relation with said motor, actuating elements arranged in desired angular position on said shaft for actuation of said guide means, and electromagnetic means for engaging said guide means to render said guide means selectively ineffective and effective to be so actuated by one of said actuating elements to maintain said sequence switch normally in one of said switching positions when ineffective and to initiate a cycle of operation of said sequence switch by all of said actuating elements when effective.

24. In a controller having a step-by-step sequence switch with a plurality of switching positions through which it is adapted to be operated cyclically to provide a cycle of signaling conditions, ratchet wheel means connected with said sequence switch, a time controlled motor, pawl means reciprocated by said motor over a path adjacent said ratchet means, means guiding said pawl means normally to maintain said pawl means disengaged from said ratchet means and adapted to be actuated to guide said pawl means into engagement with said ratchet means, a shaft rotating in predetermined time relation with said motor, actuating elements arranged in desired angular position on said shaft, and control means for engaging said guide means to render the guide means selectively ineffective and effective to be so actuated by said actuating elements whereby said sequence switch will be maintained in one of said switching positions when said guide means is rendered ineffective and said sequence switch will be operated through the cycle of switching positions when said guide means is rendered effective.

KAJ S. CHRISTENSEN.
